UNITED STATES PATENT OFFICE.

FRANK C. RODGERS, OF ST. LOUIS, MISSOURI.

DENTAL IMPRESSION TRAY.

Application filed June 16, 1920. Serial No. 389,384.

To all whom it may concern:

Be it known that I, FRANK C. RODGERS, a citizen of the United States, and residing at St. Louis, Missouri, have invented the new and useful Improvement in Dental Impression Trays, of which the following is a specification.

This invention relates to dental impression trays adapted for the purpose of taking 10 impressions of the mouth to reproduce impressions of teeth, gums, palate and adjacent structures.

One of the objects of this invention is to provide an impression tray which is so 15 shaped as to conform to the vault of the arch and the curvature assumed by the teeth and the gums so as to insure correct and accurate impressions.

Another object is to provide a dental impression tray which, while it is constructed 20 to conform generally to the parts to be reproduced, has provisions for preventing the impression material from dropping off of the tray into the mouth or throat, at the 25 same time permitting ready removal of the tray from the impression material and providing ample space for teeth that are out of alignment.

Another object is to provide a dental impression tray which is so shaped that it 30 will not gouge into the gums or interfere with the muscle attachment at any point when the tray is adjusted in the mouth.

Another object is to provide a dental impression tray in which the front flange or 35 portion is so constructed as to force the impression material against the gum and under the lip so as to conform to protruding teeth and their gums.

40 Further objects will appear from the detail description taken in connection with the accompanying drawings, in which:

Figure 1 is a perspective view of a dental impression tray embodying this invention 45 and more particularly of a tray for the upper jaw;

Figure 2 is a front elevation showing the impression material in place;

Figure 3 is a section on the line 3—3, 50 Figure 2;

Figure 4 is a section on the line 4—4, 55 Figure 3, but with the impression material removed;

Figure 5 is a perspective view of a tray, such as shown in Figure 1, but with the loose forming element thereon;

Figure 6 is a view similar to Figure 5 but with the forming element in position; and

Figure 7 is a perspective view of the 60 forming element.

Referring to the accompanying drawings, and more particularly to Figures 1 to 4 inclusive, the tray comprises a structure which may be formed of metal, such as 65 aluminum, which may be shaped by stamping or by die-casting. The structure comprises labial flanges 1 merging into the front flange 2, while arranged centrally between the flanges is a palate portion 3, forming 70 with the flanges, an arched trough. A suitable handle 4 may be formed on or attached to the body of the tray. While the trough is distally open, there is formed at its terminus a ridge 5 which is, however, very 75 shallow and which runs transversely across the flanges 1, the bottom of the trough and along the end of the palate portion.

The flanges 1 incline and curve distally so as to conform to the gums on the upper 80 jaw while the palate portion 3 is so shaped that it conforms to the vault of the arch, it having a gradual upward slope from the incisor teeth distally towards the soft palate. The bottom or base of the tray has a 85 convex curvature distally so as to correspond to the curve of the teeth, which curve is designated as the curve of Spee in order to bring the impression material close to the back teeth. The space between the flange 90 and the palate portion is concave laterally which is a distinct advantage in removing the impression tray from the impression material while in the mouth, also providing ample space for teeth that are out of 95 alignment. The form of the slope given to the palate portion and the ridge 5 makes it possible to bring the impression material in close contact with and against the tissue but prevents it from dropping off the tray 100 into the mouth or throat. In view of the fact, however, that the ridge 5 is shallow, the trough is really left open distally and while this ridge forms a post-dam for the impression material, it does not interfere 105 with the molars but permits a close impression to be made.

The marginal edges of the flanges 1 and 2 are so shaped that the tray will not gouge into the gums nor interfere with the muscle 110 attachment at any point when the tray is adjusted in the mouth. This slope corre-

2
sponds to the relative contour of the gum from the anterior teeth towards the molars, having the highest point in the front with a gradual reduction to the distal end of the tray.

The front flange 2 has a notch 6 which is adapted to receive and form a distinct rib 7 on the impression material 8. It is the practice to cut a groove in the impression material over the gum for the purpose of providing a leverage point for a tool in order to break the impression material in order to secure its removal from the mouth. The notch 6 is of such shape and size so as to provide a sufficiently enlarged rib 7, in order to permit a deep groove 9 to be cut therein so as to provide for sufficient leverage to permit breaking of the set impression on material so as to permit its removal from the mouth without requiring the cut to be sufficiently deep so as to possibly go through the impression and injure the gum.

It is sometimes necessary to take an impression of protruding teeth that form a more or less horizontal angle to the front flange of the impression tray. In accordance with this invention, as illustrated in Figures 5, 6 and 7, a loose impression forming element 10 is provided which is arranged to be placed on the front flange 2 of the tray but which is arranged to form a loose connection therewith by providing a lug 11 spaced from this element. This element is placed on the front flange 2 and centered in the notch 6, the lug 11 taking over the flange and holding it loosely in position. The inside face of the element does not only merge into the inside face of the flange but also projects distally. Accordingly the element 10, when in place, really forms a continuation of the divided parts and forms therewith an overhanging flange.

When it is desired to take an impression of the upper surface of protruding teeth and their gums, the element 10 is placed on the tray as shown in Figures 5 and 6; accordingly the impression material will be forced upward and over the surfaces of the upper teeth and gums underneath the lip and under the lip so as to take an accurate impression. When, however, the tray is removed from the mouth, this loose piece becomes separated from the tray so as to permit ready removal of the tray from the impression material.

It is obvious that various changes may be made in the details of construction without departing from the spirit of this invention; it is therefore, to be understood that this invention is not to be limited to the specific details shown and described.

Having thus described the invention, what is claimed is:

1. A dental impression tray formed to provide a distally open arched trough having

shallow post dams formed thereon and following the transverse curvature of the trough.

2. A dental impression tray formed to provide a palate portion and a surrounding trough having shallow post dams formed thereon and following the transverse curvature of the trough and palate portion.

3. A dental impression tray embodying a palate portion and a surrounding trough, characterized by a shallow dam at the distal terminus of said palate portion and trough, and following the transverse curvature of the trough and palate portion.

4. A dental impression tray embodying a palate portion formed to slope distally and a surrounding trough, and a shallow post dam at the terminus of said palate portion and said trough and following the transverse curvature of the trough and palate portion.

5. A dental impression tray embodying a palate portion and a surrounding trough, the bottom of which concaves distally in order to bring the impression material close to the back teeth.

6. A dental impression tray embodying a palate portion formed to slope distally and a surrounding trough, the bottom of which trough concaves distally in order to bring the impression material close to the back teeth.

7. A dental impression tray embodying a palate portion and a surrounding trough, the bottom of which concaves laterally and distally in order to bring the impression material close to the back teeth.

8. A dental impression tray embodying a palate portion and side flanges formed to slope distally but oppositely and which bound a distally open trough.

9. A dental impression tray having a front flange provided with a deep and tapering notch adapted to receive the impression material in order to provide a severing rib thereon.

10. A dental impression tray having an overhanging front flange portion adapted to force the impression material against the gum and under the lip.

11. A dental impression tray having an overhanging front flange portion adapted to conform to protruding teeth and their gums.

12. A dental impression tray having a flange provided with a loose impression material forming element.

13. A dental impression tray having a front flange provided with an overhanging impression material forming element.

14. A dental impression tray having a front flange provided with a notch, and a loose impression material forming element fitting said flange.

In testimony whereof I affix my signature this 28th day of April, 1920.

FRANK C. RODGERS.
